QUICK-DRIVING GLAZIER'S POINT

Eugene Weissman, Libertytown, Md.

Application July 17, 1945, Serial No. 605,569

1. Claim. (Cl. 85—15)

1
This invention relates to glaziers' points, viz., an improved quick driving glaziers' point.

One object of this invention is to provide a glaziers' point that can be very quickly driven into a window sash in any appropriate and desired location on a window-pane without the necessity of previously placing it by hand in such desired location.

Another object is to provide an improved form of glaziers' point that can be very quickly and easily removed when preparing to remove a broken pane and replace it with a new pane.

Another object is to provide an improved glaziers' point with a medially disposed stiffening ridge that resists deflection when being driven into an unusually hard part of the sash, or hard wood of which the sash may be composed.

Another object is to provide said stiffening ridge with a serrated summit that virtually saws its way through wood-grain and when being driven, and which increases its stability when it has been driven into the sash.

Other objects and important features are pointed out or implied in the following details of description, in connection with the accompanying drawings in which:

Fig. 1 is a view showing a portion of a window-sash and pane disposed horizontally as if supported on a table, work-bench or floor; a glaziers' point on the pane; and a simple form of tool that I choose to call a glazier's point driver or pull-and-push hammer (not claimed as part of the present invention), positioned for rightward movement so as to jerk the glaziers' point into the sash.

Fig. 2 is a view similar to Fig. 1, but showing a smaller part of the push-and-pull hammer whose slotted end is at the position where its movement was stopped by the cross-ridges of the glaziers' point abutting against the sash when driving of the glaziers' point was completed by a single jerk of the pull-and-push hammer.

Fig. 3 is an enlarged right-edge view of one of the glaziers' points.

Fig. 4 is a top plan view, considered with respect to the normal driving positions in the other views.

Fig. 5 is an enlarged rear-end view of the glaziers' point seated on a fragment of a pane, the broken lines being intended to show more clearly the position, end view, of the pull-and-push hammer enlarged in proportion to the enlargement of the glaziers' point.

Referring to these drawings in detail, in which,

2
similar reference numerals refer to similar parts in the several views, the invention is explained and described as follows:

This glaziers' point is a unit that includes four substantially triangular thin plane elements, 1, 1 and 2, 2 separated by ridges 3, 3, 4 and 5 that adjoin one another at the middle portion of this unit and extend thence nearly to the outer or acute apexes of said triangular elements; the two acute apexes being merged with an entering sharp point 6 at the front end of this unit.

The ridges 3, 3 are preferably of uniform height, so they provide abutments that are sufficiently high and strong to cooperate with any suitable tool for pushing or pulling the elements 6, 5 and 2, 2 into the driven position shown in Fig. 2, viz., to position where the ridges 3, 3 are substantially against the part of the sash into which the front portion of the unit is driven.

The ridge 4 is preferably rearwardly inclined from the summit of the ridges 3, 3 to substantially the apexes of the elements 1, 1, so as not to interfere with properly putting the window sash and pane; and the main purpose of this ridge is to loosely fit in a slot 7 of a suitable tool 8 that can be either pushed or pulled for driving the front end portion of the unit into the sash.

The ridge 5 is cooperative with the ridge 4 for stabilizing the summits of the ridges 3, 3, so the latter may be thinner than if unsupported; but the second and more important function of the rib 5 is to rigidify and stabilize the quite thin elements 2, 2 so they will not become detrimentally bent or deflected by their contact with wood-grain etc. in the surface being entered by the elements 2, 2. This ridge is tapered and inclined forwardly from the ridges 3, 3 substantially to the entering point 6; and its summit is preferably serrated from end to end, as seen at 9, so that, instead of wedging and tending to split the sash, it saws its way into the sash while being driven thereinto; and besides, the wood-fibers tend to rearrange themselves, thereby entering the serrations and resisting movement of the unit from its driven position.

The tool 8 is preferably of solid iron and/or steel, being preferably somewhat longer than shown, as indicated by a part being broken out in Fig. 1, and having a hand-engaging weighty enlargement 9 by which it may be pulled while its furcations 10 are against the ridges 3—3 and are straddling the ridge 4; so, if pulled sufficiently quick and far and with sufficient force,

the tool 8 acts as a hammer, by its momentum, to drive the unit from the starting position shown in Fig. 1 to the driven position shown in Fig. 2.

In operating with greatest efficiency, the sash S is supported and secured in a substantially horizontal position while the pane P (to be secured) is properly positioned; the improved glaziers' points are then placed with their plane lower surfaces on the pane; and as each one of these units is to be used, the tool 8 is placed with its bifurcated end straddling the ridge 4, and by swinging the tool to a position substantially at right angles to the surface to be entered by the glaziers' point, the latter is placed in the proper starting position which is preferably farther from the entering place than indicated in Fig. 1; then, by properly jerking the tool longitudinally, it carries the glaziers' point with sufficient momentum to drive it at a single movement to the fully driven position shown in Fig. 2. In thus driving the glaziers' point, the furcations 10 prevent the glaziers' point from turning rightward or leftward. In other words, the furcations retain the ridge 9 substantially parallel with the shaft of the tool 8, so the direction of applied force is the longitudinal direction of the ridge 5. Of course the accuracy of keeping the ridge 5 at right-angles to the surface to be entered depends on skill of the user, and the same is true as to the speed and accuracy with which the tool is manipulated for properly engaging with the respective glaziers' points and jerking them into their respective driven positions, as in Fig. 2. However, sufficient skill may soon be acquired by a little careful practice, so one of these glazier's points could be engaged and driven every two seconds after they are placed right-side-up on the horizontally disposed pane.

The construction of one of these glaziers' points is very specifically described as follows:

It is a rigid unit that consists entirely of front and rear pairs of plane thin outer-edge portions and front and rear and laterally projecting ridge-portions, the rear sides of the laterally projecting ridge-portions 3 being substantially vertical so as to form abutments for engagement and cooperation with a point-driving means, for instance, such as shown at 7-8 in Fig. 2. The front one 5 of said ridge-portions has its rear end against and united with adjoining ends of said laterally and oppositely extending ridge-portions 3, and this ridge portion 5 is tapered to a sharp entering point at 6. The front pair of said outer-edge portions 2 have acute apexes at 6 that meet and merge with said sharp driving point of the ridge-portion 5, and said ridge-portion 5 has a longitudinal base adjoining and united with inner edges of said front pair of plane thin outer edge-portions 2. The rear one of said ridge-portions 4 is substantially aligned with said front one of the ridge-portions 5 and has its longitudinal base united with inner edges of the rear pair of plane thin outer edge-portions 1 while its front end is against and united with said adjoining ends of 65 the laterally projecting ridge-portions.

With the form of tool here shown, the glaziers' points can be engaged with the opposite faces of the furcations 10 and thereby pushed into the sash, so that all the glaziers' points, at all sides 5 of the pane-seat, can be driven without the operator moving around to said sides. However, this form of tool is shown merely to illustrate the advantages of this improved form of glaziers' point which latter is the exclusive invention 10 claimed in this application.

Though I have described this form of the invention specifically, I have no intention to limit my patent protection to the precise details of construction as illustrated and as described in 15 the foregoing, for the invention is susceptible of numerous changes within the scope of the inventive ideas as implied and claimed; for instance, the thin angular elements 1, 1 could be eliminated without rendering the invention impractical. So 20 could the elements 2, 2 be eliminated.

My invention is claimed as follows:

In a glazier's point, a rigid unit that consists entirely of front and rear pairs of plane thin outer-edge portions and front and rear and laterally projecting ridge-portions, the rear sides 25 of the laterally projecting ridge-portions being substantially vertical so as to form abutments for engagement and cooperation with a point-driving means, the front one of said ridge-portions having its rear end against and united with adjoining ends of said laterally projecting ridge-portions and being tapered to a sharp entering point, the front pair of outer-edge portions having acute apexes that meet at and merge with 30 said sharp entering point, said front one of said ridge-portions having a longitudinal base adjoining and united with inner edges of said front pair of plane thin outer portions, the rear one of 35 said ridge-portions being substantially aligned with said front one of said ridge-portions and having its longitudinal base united with the inner edges of said rear pair of plane thin edge-portions while its front end is against and united with said adjoining ends of said laterally projecting ridge-portions.

EUGENE WEISSMAN.
